UNITED STATES PATENT OFFICE.

PIERRE HENRI STANISLAS, COUNT D'ESCAYRAC DE LAUTURE, OF PARIS,
FRANCE.

IMPROVEMENT IN TELEGRAPHIC SIGNALS.

Specification forming part of Letters Patent No. 39,016, dated June 23, 1863.

To all whom it may concern:

Be it known that I, PIERRE HENRI STANISLAS, Count d'Escayrac de Lauture, of Paris, in the Empire of France, have invented a new System of Signals Applicable to Nautical, Military, and other Telegraphy, which I term a "Universal Analytical Grammar of Signals;" and I do hereby declare that the following is a full, clear, and exact description of the same, reference being had to the accompanying drawings, making a part of this specification.

My invention consists in substituting for the alphabetic transcription of words certain signals and separating the lexical element or the words from the grammatical element (lections, prepositions, adverbs, &c.) of speech.

The signal for every word (verb, substantive, &c.) is invariably whatever may be the character the word plays in the sentence, which character is indicated by a distinct separate signal, which points out the case, the number, gender, tense, mood, &c., and forms the verbs, adverbs, adjectives by its being added to a substantive. I have reduced to a minimum the use of such grammatical signals.

A single expression will replace several synonymous words. The simplest ideas alone are classed under signals. As to the more complex ones, I represent them by means of two or more signals, themselves designating plain ideas. The word "barracks," for instance, I will represent by two signs or signals, signifying the one "house" and the other "soldier."

The grammatical indications and the words are designated by a single elementary signal or letter, or are inscribed in the cases of one or more tables, each of them being designated by two signals or letters, one of which is pointing out the column and the other the line upon which they meet in the table. The grammatical indications and some plain words may occupy a part of the table, and various vocabularies corresponding to dispatches of various natures may occupy in turn the rest. The use of each vocabulary is designated by a signal indicative of the nature of the very dispatch. Thus there would be vocabularies for political news and orders for war or commercial tidings. The grammatical catalogue would, partly at least, be common to all transmissions.

The annexed drawings will illustrate the application of the system. Vocabularies more detailed will require several tables, each of which is designated by a key preceding all the signals. The words are classed, not in alphabetical order, but from the nature and association of ideas they represent. The tables being translated into various languages, each dispatch is immediately reducible into those various languages.

The above method is applicable not only to such communications as are commonly transmitted by electrical telegraphy, but also to those of nautical and military telegraphies, to written correspondence, and will be readily understood by a mere inspection of the following tables. One of these tables is composed of twenty-six elementary signals or twenty-six letters, which, taken separately, will give:

- A indicates
- B indicates the first person.
- C indicates the plural number.
- D indicates the future tense.

The second table contains a series of words, and is composed as follows:

	A	B	C	D	E	F	V	X	Y	Z	W	
A												A
B			We									B
C												C
D								To Write.				D
E												E
F												F
G												G
H												H
I												I
J												J
K												K
L												L

In accordance with this principle, by means of the two above tables, the words "We shall write," will be translated thus: BC DX D, BC being the two ordinates for "we," DX for "to write," and D indicating the future tense.

I have in the annexed drawings, Sheet I

represented a specimen table for nautical telegraph. Conformably to the principles of the "analytical universal system of signals," every word is unvariable, any verb in any language is conjugated by means of the grammatical signs the indication of which may be added to that of every verb, &c. In this table each square is divided into one hundred cases, containing each a grammatical sign or a word, each word is signalized by the key on its table, by its horizontal and vertical flags. The ten squares having ten keys represented by ten flags include the nautical nomenclatures divided in ten chapters—viz., rigging, steam, working, hydrography, &c. Secrecy is obtained by any change in the order of the flags. This table may be folded up like a map. The signs or signals for names of officers, places, and other things concerning seafaring matters may be inscribed on the back or reverse of the table. The suitable place for geographical signals representing the names of places is on the maps, close to the names. The first flag next the pendant 2 may signify a harbor, a cape, a port, &c., the first flag next the pendant 3 may indicate the nation a ship belongs to. Two may be requisite for that purpose. The second and third may indicate the class or rank of the ship.

The two following dispatches translated by means of the fifth table, Sheet I in the drawings, will make the use of the tables better understood. "I ordered you to hoist the foretop-gallant studding-sail, and you have not done it." "I have on board twenty-three seamen from the brig —, wrecked on the Straits of —. Send them on shore;" which are to be translated in the following manner, viz: The first thus:

I. { 924
I order (preterite) you to hoist
{ 101 190
foretop-gallant studding-sail you not
{
perform it.

II. { 310
I to have on board 23 sailor
{ 060 — 558
to come from brig — wreck
{ 711 — 945
(part. past) in Strait — Send
{
they on shore.

The tables shown, Sheet II, are other specimens designating accessory ideas, grammatical signs, letters, figures, &c. They have four signals. First, Bavarian system, herein represented by 1 2 3 4, each grammatical sign and each word being in their respective place on the table. One of the four signals is related to each of the four divisions on each table, and each successive quarter on each table, in the manner as follows:

1	2
3	4
1	2

or

1	2	1	2
3	4	3	4
1	2	1	2
3	4	3	4

and so forth, as represented in the drawings, Sheet II, Figures 1, 2, 3, and 4.

The table Fig. 1 contains sixteen signs, expressed by two signals. The table Fig. 2 contains sixty-four signs, expressed by three signals. The table Fig. 3 contains two hundred and fifty-six signs, expressed by four signals. The table Fig. 4 contains one thousand and twenty-four signs, expressed by five signals.

In order to make the use of these tables better understood, I subjoin a few examples. The words represented by A will be signalized by 1 1 1 1 2, the first 1 indicating that the words are to be found in the first square, the second 1 (one) indicating that the words are to be found in the first case in the first square, &c., the number 2 indicating that the words occupy the second division in the last subdivision of the great square. The words represented by B will be translated in the same manner by 2 4 3 1 1. The words represented by C will be translated by 3 2 2 1 1. The words represented by D will be translated by 4 2 3 4 2, &c.

What I claim as my invention, and desire to secure by Letters Patent, is—

The within - described universal analytic grammar of signals, based on the substitution for the alphabetic transcription of words of certain appropriate conventional signals, in combination with the separation of the lexical element from the grammatical element, substantially as herein specified.

PIERRE HENRI STANISLAS,
Count d'Escayrac de Lanture.
